UNITED STATES PATENT OFFICE.

PERCY D. BREWSTER, OF EAST ORANGE, NEW JERSEY.

APPARATUS FOR TREATING CINEMATOGRAPHIC FILMS.

1,223,664.

Specification of Letters Patent. Patented Apr. 24, 1917.

Application filed April 22, 1915. Serial No. 23,024.

To all whom it may concern:

Be it known that I, PERCY D. BREWSTER, a citizen of the United States, residing at East Orange, county of Essex, and State of New Jersey, have invented certain new and useful Improvements in Apparatus for Treating Cinematographic Films, of which the following is a full, clear, and exact description.

0 The present invention relates to the chemical treatment of cinematographic film which is coated on both sides, as, for example, with light-sensitive emulsions, and its chief object is to provide convenient and effective apparatus by which each side can be treated independently of, and without affecting, the other. It is intended primarily for use in color cinematography in which photographic images of the same object are produced on both sides of the film and are then colored or dyed in different colors, as, for example, green on one side and red on the other, but it can be used for other purposes as well. To this and other ends the invention consists in the novel features of construction and combinations of elements hereinafter described.

In the accompanying drawings,

Figure 1 shows a convenient and effective form of the invention, in longitudinal section.

Fig. 2 is a plan view of the same.

Fig. 3 is a central cross section.

Fig. 4 is a view showing the preferred form of the invention in longitudinal section, and

Fig. 5 shows a cross section thereof on line 5-5 of Fig. 4.

Referring to Figs. 1, 2 and 3, the tank 1, 40 partly filled with the reagent with which the film 2 is to be treated, is provided in its top with a longitudinal opening or slot 1^a along which the film is passed, the width of the slot 1^a being slightly less than the width 45 of the space between the two series of perforations in the film, which mesh with the feed-sprocket 5. The latter is driven by any suitable mechanism, not shown, to draw the film forward at a speed depending, in general, on the rapidity of action of the reagent used, as will be readily understood. Guides of any convenient kind, as for example the metal strips 4, are provided to 50 keep the film in position.

The liquid reagent is drawn from the tank 55 by a pump 6 connected to the outlet 12 by a pipe 7 and is delivered to a longitudinal spray or jet pipe 8 extending under the film inside the tank and having perforations on its upper side by which the liquid is sprayed 60 or jetted against the exposed underside of the film as the latter travels along. Idler rollers 3 may be provided at intervals below the film to prevent sagging thereof too far into the slot, but experience indicates 65 that devices for this purpose will seldom be needed.

The air pressure in the tank is slightly reduced, below that of the surrounding atmosphere, by means of an exhauster 11 connected to the tank by a pipe 13. The effect of the slight vacuum thus produced is to hold the edges of the film snugly down upon the edges of the slot and to maintain a constant stream of air into the tank through 75 any openings into the tank at the edges of the film due to unevenness or irregularity of the film or to perforations therein extending slightly over the edges of the slot, thereby effectually preventing any liquid thrown 80 against the underside of the film from affecting the upper side.

In Fig. 4 is shown a machine for treating both sides of the film. In this case three receptacles are employed, conveniently provided by dividing the tank 1^b transversely into three compartments, 14, 15, 16. The two end compartments or tanks, 14, 16, may contain the two different reagents, for example green and red anilin dyes, while the 90 center compartment or tank 15 may contain water for rinsing or washing the film. The feed sprockets, 21, 22, are driven by any convenient mechanism, not shown, and are preferably connected, as by a chain 24, so 95 as to run at the same speed. Between the end tanks the film 2 is looped down into the center tank and is twisted 180°, so that the side which was uppermost in passing tank 14 will be the underside in passing tank 16. 100

The reagents in the tanks 14, 16 can be thrown against the film by the spray or jet method illustrated in Fig. 1, but I prefer to use revolving paddles or brushes 17, arranged across the tanks. The paddles can 105 be driven one from the other by means of belts 23, one of the shafts, for example the one at the left end of the tank 14, being pro-

vided with a pulley 23^a, Fig. 5, for connection with a suitable driving motor, not shown.

The inlet or low pressure side of the exhauster 11 is connected to the interior of the reagent tanks 14, 16 by branch pipes 18 to produce a partial vacuum in said tanks for the purpose described. Further insurance against escape of liquid to the upper side 10 of the film is afforded by directing jets of air upon the film and toward the edges thereof, from perforations 20 in a pipe 19 extending along the film at a convenient position above the same. This pipe gets its air from the 15 outlet or high pressure side of the exhauster 11, being connected thereto by a pipe 19^a. The air jets are intended to blow back to the edges of the film any liquid that in spite of the vacuum in the tank might find its 20 way to the top of the film.

The apparatus illustrated is intended primarily for dyeing in different colors, the two sides of a film bearing cinematographic images on both sides, by the well known 25 Traube method or, preferably, by bleaching the film on both sides, preferably by treatment with iodin in a solution of potassium iodid, and then dyeing the film, usually red on one side and green on the other. The 30 dyes, in the form of aqueous solutions, are in the two end tanks. Where the time of treatment is the same for both sides of the film the strengths of the dye solutions can be adjusted to give each side its own proper 35 depth of color. For instance, if a green solution acts more slowly than a red solution of equal strength the former can be made stronger so as to bring its "speed" up to that of the other.

40 The amount of dye carried from the first tank into the wash-tank is ordinarily so minute relatively to the amount of water that is used in the latter as to have no appreciable effect on the undyed side of the 45 film even in treating a long length of the latter, it being of course understood that the water is changed frequently enough to prevent too great an accumulation of the dye. If desired, a stream of water can be kept 50 flowing through the wash-tank by providing the latter with an outlet, as 25, and an inlet pipe, as 26, connected with a suitable source of water.

It is to be understood that the invention is 55 not limited to the constructions herein specifically illustrated and described, but can be embodied in other forms without departure from its spirit.

I claim:

60 1. In a film-treating machine, in combination, a tank adapted to contain a reagent and having an opening through which the contents of the tank can reach the film, means for passing a film over said opening 65 and in contact with the edges thereof where-

by only one side of the film is exposed to the interior of the tank, means for bringing the reagent into contact with the side of the film exposed thereto through said opening, and means for creating a partial vacuum 70 in the tank.

2. In a film-treating apparatus, in combination, a tank adapted to contain a reagent and having a film-treating opening in its upper portion but being otherwise closed, 75 means for passing a film over said opening and in contact with the edges thereof, means for bringing the reagent into contact with the side of the film exposed thereto through said opening, and an exhauster connected 80 with the tank to produce a partial vacuum therein.

3. In a film-treating apparatus, in combination, a tank adapted to contain a reagent and having a film-treating opening in its 85 upper portion, means for passing a film over said opening and in contact with the edges thereof, and means in the tank for bringing the reagent into contact with the side of the film which is exposed through said opening. 90

4. In a film-treating apparatus, in combination, a tank having a film-treating opening in its upper portion but being otherwise closed, means for passing a film over said opening and in contact with the edges thereof, means for projecting a reagent through said opening and against the exposed side of the film, and air-exhausting means connected with the tank to produce a partial 95 vacuum therein.

5. In a film-treating apparatus, in combination, a tank having a film-treating opening in its upper portion, means for passing a film over said opening and in contact with the edges thereof, means for projecting a reagent through said opening and against the inner side of the film, and means for discharging jets of air against the outer surface of the film. 105

6. In a film-treating apparatus, in combination, a tank having a film-treating opening in its upper portion but being otherwise closed, means for passing a film over said opening and in contact with the edges thereof, means for projecting a reagent through 110 said opening and against the inner side of the film, means for producing a partial vacuum in the tank, and means for discharging jets of air against the outer surface of the film. 115

7. In a film-treating apparatus, in combination, a tank having a film-treating opening in its upper portion, means for passing a film over said opening and in contact with the edges thereof, means for projecting a reagent through said opening and against the inner side of the film, air-exhausting apparatus having an inlet connected with the tank to produce a partial vacuum therein, and means receiving air from an outlet of 120 125 130

said exhausting apparatus and discharging it against the outer surface of the film.

8. In a film-treating apparatus, in combination, a pair of tanks each having a film-treating opening in its upper portion, means for passing a film over the openings in succession and in contact, the film being twisted between the tanks whereby the edges thereof with one side of the film is exposed to the 10 interior of the first tank and the other side is exposed to the interior of the other tank, means for producing a partial vacuum in the tanks, and means in each of the pair of tanks to project a reagent against the exposed side of the film.

9. In a film-treating apparatus, in combination, a pair of treating tanks each having a film-treating opening in its upper portion, means for passing a film over the openings in succession and in contact with the edges thereof, the film being twisted between the tanks whereby one side of the film is exposed to the interior of one tank and the other side is exposed to the interior of the 25 other tank, a washing tank between the treating tanks, means in each treating tank for projecting a reagent against the exposed side of the film, and means for producing a partial vacuum in the treating tanks.

10. In a film-treating apparatus, in combination, an elongated tank having a longitudinal slot in its top and being otherwise closed, a film-feeding sprocket to draw a film along the top of the slot with the under- 35 side of the film exposed to the interior of the tank, means for projecting a reagent upwardly against the exposed underside of the film, and an exhauster connected with the tank to produce a partial vacuum therein.

11. In a film-treating apparatus, in combination, a pair of treating tanks each having a film-treating opening and each adapted to contain a reagent, means in each tank for bringing the reagent therein into contact 45 with the exposed side of the film, a wash-tank between the treating tanks, a sprocket arranged to draw a film over the opening in one treating tank and into the washing tank, a sprocket arranged to draw the film out of 50 the washing tank and over the opening in the other treating tank, and means for driv-

ing the sprockets to produce a uniform movement of the film over both said openings.

12. In a film-treating apparatus, in combination, a pair of treating tanks each adapted to contain a reagent and each having a film-treating opening for exposing a film to the reagent, means in each tank for bringing the reagent therein into contact 55 with the exposed side of the film, a washing tank between the treating tanks, and means for passing a film over the opening in one tank, into the washing tank, and over the opening in the other tank, in succession. 60

13. In a film-treating apparatus, in combination, a tank adapted to contain a reagent and having an opening for exposing a film to the reagent, means for passing a film over said opening with one side of the 70 film exposed to the interior of the tank, means for bringing the reagent into contact with the exposed side of the film, and means operating to prevent access of the reagent to the outer surface of the film. 75

14. In a film-treating apparatus, in combination, a tank adapted to contain a reagent and having an opening for exposing a film to the reagent; means for passing a film over said opening with one side of the 80 film exposed to the interior of the tank, means for bringing the reagent into contact with the exposed side of the film, and means, comprising an exhauster connected with the tank, operating to prevent access of the re- 85 agent to the outer surface of the film.

15. In a film-treating apparatus, in combination, a tank adapted to contain a reagent and having an opening for exposing a film to the reagent, means for passing a 90 film over said opening with one side of the film exposed to the interior of the tank, means for bringing the reagent into contact with the exposed side of the film, and means operating to cause greater air pressure on 95 the outer side of the film than on the inner side, whereby to prevent access of the reagent to the outer surface of the film.

In testimony whereof I hereunto affix my signature.

PERCY D. BREWSTER.
